UNITED STATES PATENT OFFICE.

FRANCIS W. CHAUSSÉ, OF PORTLAND, OREGON.

SASH-LOCK.

1,020,637.

Specification of Letters Patent. Patented Mar. 19, 1912.

Application filed March 31, 1909, Serial No. 486,896. Renewed August 12, 1911. Serial No. 643,785.

To all whom it may concern:

Be it known that I, FRANCIS W. CHAUSSÉ, a citizen of the United States, residing at Portland, in the county of Multnomah and State of Oregon, have invented a new and useful Improvement in Sash-Locks, of which the following is the specification.

This invention relates to improvements in devices for locking sashes.

10 The object of the invention is to provide convenient means for adjusting the upper and lower sashes for ventilation and fastening them together to prevent unauthorized persons moving said sashes farther from the outside to gain admission to the room.

15 The invention also comprehends improvements in the specific details of construction and arrangement of parts, to be hereinafter described and particularly pointed out in 20 the claims.

In the drawings:—Figure 1, is a perspective view of my improved sash lock. Fig. 2, is a vertical view, illustrating the locking bolt withdrawn. Fig. 3, is a similar view 25 showing the sashes adjusted and the locking bolt in locking position. Fig. 4, is an enlarged detail sectional view of the locking bolt and its casing. Fig. 5, is a side elevation of the locking bolt casing.

30 Numeral 1, indicates a casing provided with a flange 2, the casing fitted in an opening 3, formed in the lower sash 4. The casing is open at its inner end and formed at its opposite end with a threaded opening 5, 35 and in its side wall is provided with a longitudinal slot 6, having an angular portion 7. Slidably mounted in the casing is a plunger 8, provided with a reduced stem 9, having a threaded portion 10, on the outer end of 40 which is a finger piece 11. Extending from the side of the plunger 8, is a lug or projection 12, operating in the longitudinal slot 6, and the angular portion 7, as will be herein- 45 after described. Interposed between the plunger 8, and the front wall of the casing 1, is a coil spring 13, which normally tends to force the plunger outwardly beyond the open end of the casing as shown in Fig. 4.

The upper sash 15, of the window is 50 formed with a mortise or cut out portion 16, to receive a thin strip 17, formed with a plurality of openings or seats 18, which register with openings or depressions in said sash. The strip 17, is permanently fastened 55 to the upper sash in any preferred manner.

In operation, assuming the plunger to be

withdrawn in the casing as shown in Fig. 2, the finger piece 11, is turned slightly to disengage the lug or projection 12, from the angular portion 7, of the slot in the casing, 60 until said projection is in alinement with the slot 6, whereupon the spring 13, projects the plunger beyond the edge of the casing, the threaded portion 10, of the stem limiting the outward movement of said plunger. 65 After the spring has projected the plunger, and the projection 12, is beyond the casing, the operator then turns the finger piece 11, to engage the threads of the stem with the threaded opening, and upon continued rotation of the finger piece the plunger is forced forward in one of the openings 18, in the upper sash, causing a binding or locking action between the two sashes. By this operation the end of the plunger engaging the 70 upper sash, tends to force it outward while the lower sash is forced in the opposite direction. Obviously by this binding of the parts the two window sashes are held rigidly together and thereby prevented from 75 rattling. The invention therefore comprehends means for not only locking the two sashes, but also the binding of the sashes in such manner as will hold them rigid in their frames. The openings or seats in the strip 80 17, are rectangular to insure the entrance of the plunger as will be readily understood. To unlock the window sashes the finger piece is turned to cause the threads to retract the plunger and then by slightly withdrawing said finger piece the projection 12, is brought into register with slot 6, and then a slight lateral movement is given to said finger piece to cause the projection to fit into the angular portion of the slot and thereby 85 prevent the spring forcing the plunger out of the casing. In this position the sash may be adjusted to suit the convenience of the operator.

The invention is exceedingly simple, and by reason of the few parts is not liable to become out of order, and is effective for the purpose for which it is designed.

What I claim is:

1. A sash lock comprising a casing for attachment to a window sash, and formed with a threaded opening and a slot having an angular portion, a plunger operating in the casing, a threaded stem extending from the plunger, a projection on the plunger which 105 operates in the slot, and a strip for attachment to the companion sash, said strip having 110

- ing a series of seats with which the plunger engages, the threaded portion of the stem being located so as to engage the threaded opening in the casing after the projection 5 has passed the end of the slot to lock the two sashes together.
2. A sash lock comprising a casing for attachment to a window sash and formed with a threaded opening, a plunger operating in 10 the casing, a stem extending from the plunger and formed with a threaded portion to engage the threaded opening in the casing when the plunger is projected beyond said casing, a spring interposed between the 15 casing and the plunger to normally project the latter and a strip for attachment to the companion sash and formed with seats to receive the plunger, the threaded connection between the stem and the casing binding 20 the two sashes together.
3. A sash lock comprising a casing for attachment to a window sash and formed with a threaded opening, a plunger operating in 25 the casing, a stem extending from the plunger and formed with a threaded portion to engage the threaded opening in the casing when the plunger is projected beyond said casing, a spring interposed between the 30 casing and the plunger to normally project the latter, and means for holding the plunger withdrawn in the casing.

4. A sash lock comprising a casing for attachment to a window sash and formed with a threaded opening, a plunger operating in 35 the casing, a stem extending from the plunger and formed with a threaded portion to engage the threaded opening in the casing when the plunger is projected beyond the casing, a spring interposed between the casing and the plunger to normally project the latter, and means including a slot for guiding the plunger in the casing when said plunger is withdrawn and locking the latter in withdrawn position after the threaded 40 stem is disengaged from the threaded opening.

5. In a locking device of the character described, comprising a casing formed at one end with a threaded opening and open at its 45 opposite end, a plunger operating in the casing, a stem connected to the plunger and having a threaded stem, passing through the opening in the casing, said threads on the stem being located to engage the threads 50 in the opening when the end of the plunger is projected beyond the open end of the casing to lock said plunger in its projected position, and a spring for normally projecting the plunger.

FRANCIS W. CHAUSSÉ.
